Primary Examiner—Susan J. Lucas*Attorney, Agent, or Firm*—Watts, Hoffmann, Fisher & Heineke[57] **CLAIM**

The ornamental design for a lamp, as shown and described.

DESCRIPTION

FIG. 1 is a perspective view of a lamp showing my new design as embodied in a ceiling lamp;

FIG. 2 is a front elevational view thereof, the rear and side elevational views being identical;

FIG. 3 is a top plan view thereof;

FIG. 4 is a bottom plan view thereof;

FIG. 5 is a sectional view as seen approximately from the plane indicated by the line 5—5 in FIG. 2;

FIG. 6 is a perspective view of a second embodiment of my new design as embodied in a floor lamp;

FIG. 7 is a front elevational view thereof the rear and side elevational views being identical;

FIG. 8 is a top plan view thereof; and,

FIG. 9 is a bottom plan view thereof.

The ceiling plate and the base are shown in broken lines for illustrative purposes only and form no part of the claimed design.
